UNITED STATES PATENT OFFICE

CLARENCE S. JOHNSTON, OF AMARILLO, TEXAS

EXPANSIBLE PISTON

Application filed November 28, 1930, Serial No. 498,800. Renewed April 21, 1932.

This invention relates to certain new and useful improvements in pistons and the primary object of this invention is to provide an expansible piston that may be readily and 5 manually expanded for compensating for wear on the periphery of the piston.

The primary object of this invention is to provide a piston formed of one piece, that is to say a piston, the head and skirt of which 10 are integral, together with means incorporated with the piston to facilitate expanding the piston.

A still further object of the invention is to provide an expanding piston, that may be 15 uniformly expanded, so as to insure uniform diameters throughout the length of the piston when the latter is expanded, and further, to provide such an expanding piston, that will be strong, durable, and which will be 20 thoroughly practical and efficient in operation.

Other objects and advantages of the invention will become apparent during a study of the following description, taken in connection 25 with the accompanying drawings wherein:

Figure 1 is an elevational view of the piston.

Figure 2 is a bottom plan view thereof. 30 Figure 3 is a vertical transverse sectional view taken substantially on the line 3-3 of Figure 2.

Figure 4 is a fragmentary vertical sectional view taken substantially on the line 4-4 of Figure 3.

With reference more in detail to the drawings, it will be seen that the expanding piston is formed of one piece, and of suitable material and includes a head 5 and a skirt 6, 40 the piston in its entirety being hollow, and the head provided with the usual grooves for receiving the piston rings 7.

In carrying out my invention, the piston is split circumferentially at the junction of 45 the head 5 and skirt 6 as at 7.

On diametrically opposite sides thereof the skirt 6 of the piston is provided with a substantially U-shaped opening 8 that extends downwardly from the split 7 between the 50 skirt and head. Integral with the wall of

the skirt and extending across the opening 8 is a boss 9 which boss 9, adjacent its longitudinal edges is provided with slots 10 forming connecting webs 11 that are integral with the wall of the skirt adjacent the side edges of the opening 8. Intersecting each slot 10 is a vertical bore 12 that tapers longitudinally and has its smaller end at the upper end of the boss 9. Each of the bores 12 is internally threaded and a longitudinally tapering elongated set screw 13 is screwed into the bore, each set screw at its lower end being provided with a squared head whereby a suitable tool may be associated therewith for screwing the set screw upwardly with respect to the bore. 55 60 65

The skirt 6 adjacent each opening 8 is split obliquely as at 14 from the lower edge of the skirt to the lower end of the opening 8. 70

From the foregoing it will be seen that by threading the screws 13 upwardly of the respective bores 12, the slots 10 will be expanded, resulting in an expansion of the entire cylinder throughout its length, with the result that when expanded, the piston will maintain the uniform diameter throughout its entire length. 75

Each boss 9 at its upper end merges into an integral connecting web 15 rising from the boss, which web 15 is also integral with the head 5 as shown to advantage in Figures 1, 3 and 4. 80

On its inner face, each of the bosses 9 is recessed as at 16, and opposite the recess, the boss is provided with a suitable aperture 17 that is counterbored as at 18 for accommodating one end of a suitable wrist pin shown in Figure 4 and designated generally by the reference character 19. 85

From the foregoing it will be apparent that the boss, having web 15 integral therewith, and integral with the head 5, and in turn being integral with the skirt 6 through the medium of the connecting portions or webs 11, that the head 5 and skirt 6 are substantially integral one with the other, and incapable of axial movement relative to one another. 90 95

The piston being split, at 7, and on dia- 100

metrically opposite sides of the skirt as at 14, together with the provision of the diametrically opposed openings 8 will permit of expansion of the piston without distorting the latter.

5 From the foregoing then it will be seen that I have devised a piston, that may be readily and easily expanded, and which when expanded, will maintain uniform diameter throughout its length.

10 Even though I have herein shown and described the preferred embodiment of the invention, it is to be understood that the same is susceptible of changes, modifications and arrangements coming within the scope of the 15 appended claims.

Having thus described my invention, what I claim as new is:

1. An expandible piston including in combination a skirt provided on diametrically opposite sides with an opening, a boss integral with the skirt at opposite sides of each opening, each of said bosses provided with slots opening inwardly from one face thereof and means for expanding the slots for effecting expansion of the piston.

2. An expansion piston including in combination a skirt provided on diametrically opposite sides thereof with openings, a boss opposite each of said openings and integral with the skirt adjacent opposite sides of the respective openings, each of said bosses adjacent opposite vertical edges provided with a slot opening inwardly from one face of the boss and expanding means engageable with each slot.

3. An expandible piston including a skirt apertured at opposite sides thereof, a boss adjacent each aperture, connecting webs integral with the boss and skirt at opposite sides of the aperture, and wedge means between said webs and adjacent portions of the boss for effecting an expansion of the piston.

4. An expandible piston including in combination a head and a skirt, said piston being split circumferentially at the junction of said head and skirt, oppositely disposed bosses arranged in the piston for supporting a wrist pin, each of said bosses provided with a web united with said head, together with oppositely disposed webs united with said skirt, whereby provision is made for retaining the head and skirt against axial movement relative to one another, and means interposed between the bosses and the webs united with said skirt for effecting radial expansion of the skirt.

5. A piston including a radially expandible skirt, and means for expanding said skirt, said means including a member provided with webs united with said skirt in spaced relation with respect to one another, and means interposed between said webs and said member for effecting a movement of the webs

in relatively opposite directions to thereby radially expand said skirt.

In testimony whereof I affix my signature.

CLARENCE S. JOHNSTON.
